United States Patent Office

Des. 224,616
Patented Aug. 15, 1972

224,616

LIQUID CONTAINER

Warren J. Schieser, Columbus, and Jere C. Marsh,
Worthington, Ohio, assignors to The Corrugated Container Company, Columbus, Ohio

Filed May 7, 1971, Ser. No. 141,453

Term of patent 14 years

Int. Cl. D9—03

U.S. Cl. D9—175

FIG. 3

FIG. 5

FIG. 1 is a plan view of a liquid container embodying our new design;

FIG. 2 is a side elevational view;

FIG. 3 is a bottom plan view;

FIG. 4 is a front elevational view; and

FIG. 5 is a sectional view taken along line 5—5 of FIG. 2.

We claim:

The ornamental design for a liquid container, substantially as shown.
